UNITED STATES PATENT OFFICE.

SEXTUS A. EDDINS, OF QUINCY, MASSACHUSETTS, ASSIGNOR TO CORDO-HYDE CO., A COPARTNERSHIP CONSISTING OF FRANCIS HANNIGAN, OF BRAINTREE, MASSACHUSETTS, AND SEXTUS A. EDDINS, OF QUINCY, MASSACHUSETTS.

SHOE-UPPER SUPPORT.

Application filed March 24, 1924. Serial No. 701,284.

This invention relates to footwear, and it is especially concerned with the problem of preserving the fit, shape and style of a shoe.

The great majority of women's and misses' 5 shoes now worn are of the low types, the single or double strap styles, pumps, and the like, being very common. Such shoes after a very short period of wear tend to wrinkle through the shank and the upper sags, thus 10 giving to the entire shoe an unattractive and sloppy appearance, in marked contrast to the neat, trim and stylish appearance which the shoe originally possessed.

The present invention deals with the problem 15 presented by these conditions, and it aims to devise a support for the upper of a shoe which will preserve its shape, improve its fit, and enable the shoe to retain its dressy appearance much longer than it would otherwise. It is a further object of the invention 20 to devise a support for the shoe upper which, while answering the above requirements, will be economical to manufacture, and will not interfere with the present shoe manufacturing processes.

The nature of the invention will be readily 30 understood from the following description when read in connection with the accompanying drawings, and the novel features will be particularly pointed out in the appended claims.

Referring now to the drawings,

Figure 1 is a side elevation of the greater 35 portion of a last having an insole attached to the bottom thereof, and showing a support embodying this invention applied to the last;

Fig. 2 is a plan view of the parts shown in Fig. 1;

Fig. 3 is a bottom view of the parts shown 40 in Fig. 1;

Fig. 4 is a cross sectional view substantially on the line 4—4, Fig. 1; and

Fig. 5 is a perspective view of the support.

In the drawings, 2 designates a last, and 45 3 an insole tacked thereon. The shoe upper support or stiffener provided by this invention is intended to be located in the shoe between the lining and the upper leather (commonly designated the "upper") so that 50 it is entirely concealed from view. As shown in the drawings, this support comprises two wings designated at 4 and 5, respectively,

and a bridge 6 which connects the lower edges of these wings and is integral with them. The wings are made of some thin, stiff, sheet material having sufficient resiliency to retain its shape and offer a substantial resistance to distortion, while at the same time yielding to accommodate the movements of the foot. The shape of the wings necessarily will depend, to some extent, on the design and character of the shoe in which it is to be used, but it is preferable to make each wing of such a length that it will extend from a point in the wide portion of the heel part of the shoe forward almost to the junction of the shank and forepart. On the inside of the shoe the forward edge of the wing should lie somewhat behind the great toe joint, and on the outside of the shoe it should be located just behind the little toe joint, so that as the shoe flexes the outline of the support or stiffener will not be seen, and it will offer no resistance whatever to the normal bending movements of the shoe in walking. The wings should be high enough to extend from a line close to the edge of the insole or the welt crease upwardly to a point opposite the upper part of the foot. In other words, these wings should be of such area and so disposed that they will support those parts of the upper which normally are not subjected to flexing, but which do, nevertheless, tend to sag and become misshapen as 70 75 80 85 above described.

The bridge 6 extends across the bottom of the foot and preferably is very much shorter than either wing so that the movements of the end portions of the wings will not be restricted by the connection of the wings with the bridge. The chief function of the bridge is to hold the two wings in the proper relationship to each other, while still permitting them to spring apart to accommodate 90 95 the foot.

The method of assembling this support in a shoe will depend somewhat on the method of shoe making employed and the type of shoes in which it is used. In McKay shoes 100 the support should be inserted after the assembling operation has been performed, the wings being slipped in between the upper and the lining, and the bridge resting on the insole to which it may be secured by a single 105 tack. When the stitching operation is per-

formed to unite the insole, outsole and upper, the stitches will go through the bridge and secure it firmly in the shoe.

- In making Goodyear shoes, it is preferable to split the insole from the heel end back to a point in the shank forward of the position to be occupied by the front edge of the bridge. The support should be slipped in place in the same manner as in a McKay shoe except that the bridge will be located between the split sections of the insole. It can be held in this position by a single tack driven through the bridge and the innerhalf of the insole and clinched on the inside, and the two sections of the insole may then be secured together back of the bridge. The outer part of the insole will carry the lip to which the upper and welt will be secured in the usual manner.
- 20 The selection of a proper material from which to make the support has proved to be a troublesome problem, but I have found that sheet celluloid is best suited to this purpose. The celluloid should not be greater in thickness than thirty thousandths nor less than fifteen thousandths of an inch. I prefer to use celluloid of about twenty thousandths of an inch in thickness. The support is cut out of the celluloid by means of a pattern or die of suitable form, and it is then molded to the contour of the last on which the shoe is to be built. In order to perform this molding operation the celluloid may conveniently be immersed in hot water and then ironed to the form of the last, or it can be shaped by suitable molds. In any event, the entire support should be made to fit the last accurately, as shown in the drawings, and the opposite sides of the bridge preferably should be shouldered or creased, as shown at 7—7, so that the stiffener will fit accurately over the corresponding edges of the insole 3 and hug the sides of the last tightly. Preferably, also, the edges of the wings should be bevelled or skived so that when the support is in its normal position in a shoe there will be no appreciable tendency for the upper to wrinkle and reveal the outline of some part of the support.
- 50 I have definitely determined that such a support when properly placed in a shoe greatly reduces the tendency of the upper to sag; it preserves the style and neat appearance which the shoe originally has; and it enables the shoe to retain its original shape and attractive appearance for a very much greater length of time than otherwise would be the case. Furthermore, such a support contributes to the comfort of the shoe and tends to preserve the fit of the upper of the

shoe around the foot. It is obvious that a device of the character shown and described can be manufactured very economically so that it increases the expense of the shoe by only a trifling degree. Furthermore, the building of this device into a shoe does not interfere in any material respect with the normal shoe manufacturing processes nor cause any material increase in the expense of manufacture.

65 While, as above stated, I prefer to make this support of celluloid, it is contemplated, nevertheless, that it can be made of other materials.

70 Under some circumstances, and particularly where the support is to be incorporated in a high shoe, it is preferable to perforate the wings in order to afford a certain amount of ventilation, and to reduce any tendency of the device to confined the heat of the foot to 75 an undesirable degree.

75 No claim is made in the present application to a shoe including a support of the character above described, but such claims are made in my companion application Serial No. 701,285, filed of even date herewith.

80 Having thus described my invention, what I desire to claim as new is:

85 1. A support for the upper of a shoe, comprising two wings of thin, stiff, resilient, 90 sheet material, said wings being shaped to fit between the lining and upper of a shoe in the region between the heel and forepart at opposite sides of the shoe and serving to hold the upper in its original shape, and a bridge 95 connecting the lower edges of said wings and integral with them, said bridge being shouldered at its opposite sides to accommodate the corresponding edges of the insole 100 of the shoe.

105 2. A support for the upper of a shoe, comprising two wings of thin, stiff, resilient, sheet material shaped to fit between the lining and upper of a shoe at opposite sides thereof and tending to hold the upper in its original shape, each of said wings being long enough to extend from a point in the wide portion of the heel part of the shoe forward to a point near the junction of the shank and forepart and being of sufficient height to extend from the insole up to a point opposite the upper part of the foot, a bridge connecting the lower edges of said wings and integral with them, both of said wings extending forward for a substantial distance beyond their points of connection with the bridge, and shoulders at the opposite sides of the bridge to accommodate the corresponding edges of the insole of the shoe.

110 SEXTUS A. EDDINS.
